ARTIFICIAL REFRIGERATION

Daniel Thew Wright, Washington, D. C.

Application May 16, 1933, Serial No. 671,382

1 Claim. (Cl. 62—119.5)

This invention relates to an improvement in closed circulating cooling systems for refrigerators.

It is conventional in absorption systems of refrigeration to cause the refrigerant to cyclically move from a generator through a condenser, an evaporator, an absorber, exchangers and back to the generator. The cooling for the absorber and the condenser is effected by the use of water in many commercial systems. Cooling by water possesses many advantages over air cooling; first water is practically always much below room temperature and second its use requires no moving parts or energy consuming equipment.

15 The water cooling system for a refrigerator is connected in to the water system of the house or building, the water flowing from the house lines through the closed cooling system and thence to the sewer.

20 Considerable difficulty has been experienced in the past in the use of the closed water cooling systems because when the source of supply is cut off the cooling system will not drain. In many localities refrigerators are used only in the 25 summer months, being shut off during the winter when natural cooling precludes the necessity for artificial refrigeration. Furthermore, in summer homes and like places it is often desirable to shut off the refrigerator during periods of absence of the occupants. With the equipment heretofore employed the refrigerator could be shut off but the cooling system remained filled or substantially filled with water. In cold weather the water freezes and bursts the cooling system. Additionally, the condensing coil for the refrigerant is usually metallically bonded to the water coil and the bursting of the water coil therefore virtually destroys the entire refrigerating unit.

35 Because of these disadvantages absorption systems of refrigeration have not been adopted by many people who otherwise would use them.

It is the purpose and object of the present invention to overcome the difficulties above 45 enumerated and provide a closed water cooling system which can be quickly and expeditiously drained.

The specific nature and characteristics of the invention will be made apparent as the description proceeds.

The invention is more or less diagrammatically illustrated in the accompanying drawing to which reference will now be made.

40 The refrigerator unit embraces generally the gas heated generator A, the rectifier B, the re-

frigerant condenser coil C, the expander D, exchanger E and absorber F. The refrigerant, i. e., ammonia vapor is liberated in the generator A, passes through rectifier B and is condensed in coil C. The liquid ammonia comes in contact with the hydrogen in the expander or evaporator D and evaporation with resultant cooling or refrigeration occurs. The heat laden ammonia vapor and hydrogen now pass to the absorber F. Here they separate. The hydrogen returns to the expander D while the ammonia vapor is absorbed in distilled water, and returns to the generator A.

45 Now, coming to the closed water circulating system for cooling the absorber F and the ammonia condensing coil C, it will be observed that a water main or house line 1 is provided. The line 2 leads to a low point 3 from which line 4 leads to the coil 5 encircling the absorber F. A vertical line 6 leads the water from coil 5 to 50 the coil 7 which latter coil is in juxtaposition and metallically bonded to the ammonia condensing coil C. The coil 7 terminates in a line 8 leading into pressure regulator 9 communicating in turn with the discharge line 10 which is connected to the sewer 11.

55 The line 2 is provided with a control valve 12 for shutting off the source of water supply to the cooling system. The valve 12 is placed in a section of the pipe 2 which preferably inclines 30 toward the supply line 1 so that when the water system of the house is drained the portion of the pipe 2 between the valve 12 and the main 1 will drain back into the main 1.

The gate valve 12 is provided on the cooling system side with a small disc vent cock 13 which may be of any suitable construction, for example, it may be similar to a radiator valve.

60 A by-pass line 14 provided with valve 15 connects the low point 3 of the system with the discharge line 10 or the sewer 11.

It will be observed that the cooling system is a closed one and that when the valve 12 is open with vent cock 13 and valve 15 closed, the cooling water flows from house line 1 through the system 45 including pipes 2, 3, coil 5, pipe 6, coil 7, pipe 8, pressure regulator 9, and pipe 10 to the sewer 11.

65 Now, if the valve 12 is closed, and vent cock 13 and valve 15 left closed, the system will not drain. The water in pipe 10 may finally seep 50 out but no flow beyond pipe 10 will occur. The coil 7, pipe 6, coil 5, and pipes 2 and 4 remain full of water and are subject to being frozen with the accompanying damage. If valve 15 is opened, the closed system still will not drain because 55

there is no available air to displace the water in the system. It, therefore, becomes necessary to open both valve 15 and the vent cock 13 in order to completely drain the system. Opening vent 5 cock 13 is alone insufficient to effect the draining of the closed system because the coils 5 and 7 trap the water against flow through pipe 10.

When valve 12 is closed and vent cock 13 and valve 15 opened, the system will complete drain 10 as follows: Water in pipes 2 and 4, coil 5, line 6, and coil 7 will all drain out through line 14 and valve 15 while the water in line 10 flows down therethrough.

Of course, it is obvious that the supply main 15 and sewer may not always be located as shown in the drawing but in order to effectively drain the closed system it is essential that a low point in the system be connected by a valve controlled drain pipe to the discharge line or sewer and that 20 an air vent be present for admitting air to the closed system to displace the entrapped water therein.

The specific forms of valve shown are not essential since various types of appropriate valves 25 may be employed.

From the foregoing it will be apparent that the invention provides an efficient closed circulating system for refrigerators which can be conveniently and expeditiously drained at will.

Having thus described my invention, what I 5 claim is:—

In a refrigerating unit of the character embracing a condensing coil and an absorber for the refrigerant, a closed water circulating system adapted to be interposed between the water supply main and the sewer including a water coil surrounding the absorber and a water coil in juxtaposition to the condensing coil, the water in said water coil being normally trapped against flow when the source of supply is shut off, a valve 15 for shutting off the system from the supply main, a discharge pipe connecting the system to the sewer, a second valve controlled drain pipe connecting a low point in the system to the sewer and an air vent cock for admitting air to the system to displace the water therein when the system is shut off from said supply main and said valve controlled drain pipe is opened.

DANIEL THEW WRIGHT. 25
